CLAIM

The ornamental design for a feed stick holder for birds and other small animals, as shown and described.

DESCRIPTION

FIG. 1 is a perspective view of a feed stick holder for birds and other small animals showing my new design. The dot-dash lines represent a feed stick, which is not part of the present invention.

FIG. 2 is a left side view of the holder, the right side view being a mirror image thereof.

FIG. 3 is a front view.

FIG. 4 is a top view.

FIG. 5 is a rear view; and,

FIG. 6 is a bottom view.
